ATTORNEY

UNITED STATES PATENT OFFICE.

THOMAS H. CHADWICK, OF ARNOLD, PENNSYLVANIA.

FLUSH TANK.

Application filed April 4, 1928. Serial No. 267,323.

My invention relates to flush tanks, such as are used in connection with toilets, and it consists in the combinations, constructions, and arrangements herein described 5 and claimed.

An object of the invention is to provide a removable guide means for a flush valve, so formed as to guide the flush valve directly to its seat, thus preventing possible off-seat-10 ing of the flush valve.

A further object of the invention is to provide a stop means for the flush valve, the stop means preventing unnecessary movement of the flush valve and its associated parts.

15 A further object of the invention is to provide a float valve, arranged to prevent overflow of the container when the valve is seated.

20 A further object of the invention is to provide an arrangement for removably securing the float valve holding means to the cover plate of the container.

25 A further object is to provide in a device of the above mentioned character, means for positive operation in varying water pressures.

30 A further object is to provide an arrangement of parts, so simple in construction that even those unskilled in the practice may make repairs, and replace worn parts.

Other objects and advantages will appear in the following specification, and the novel features of the invention will be particularly pointed out in the appended claims.

35 In the drawings:

Figure 1 is a sectional view of the device embodying my invention,

Figure 2 is a vertical sectional view taken on line 2—2 of Figure 1,

40 Figure 3 is a horizontal sectional view on line 3—3 of Figure 1,

Figure 4 is a view similar to that of Figure 1, showing the apparatus in a different position.

45 In carrying out the invention use is made of a container 1, which may be of any conventional form. A gasket 2 and a cover-plate 3 are secured upon the top of the container 1 by means of screws 4, or other suitable fastenings.

50 A water supply pipe 5 is introduced at the bottom of the container 1, and is provided with a shut-off valve 6.

55 That portion of the supply pipe 5, within the container 1, is curved in such a manner

as to direct the force of incoming water upon the bottom of the container 1.

A pair of spaced apart downwardly projecting lugs 7, are secured to the cover-plate 3 within the container. These lugs are 60 formed with arcuate slots 8 to receive and retain the ends of a pivot shaft 9^a to which is secured a rocker arm 9, and to permit the ready removal of said shaft.

One end of the rocker arm 9 terminates in 65 a ring portion 10, which is adapted to receive a float valve 28. A groove 11 is formed in the opposite end of the rocker arm 9 to receive a connecting link 19. The groove 11 is of a V shape and permits, ease of assembly. 70

An outlet pipe 12 is positioned in the bottom of the container 1, and has its upper end formed to provide a seat 13 for a flush valve 14. A water tight joint is made between the outlet pipe 12 and the bottom of the container 1, by means of a lock nut 15 and suitable washers 16.

75 A valve stem 17 is screw-threaded or otherwise conveniently fastened into the top of the valve 14. The free upper end of the valve stem 17 is turned or bent substantially at a right angle to the body of the stem forming a stop 18.

80 A wire link 19 connects the rocker arm 9 with the valve stem 17. The link 19 is formed at its upper end with an eyelet 20 to engage in the groove 11 of the rocker arm 9. The opposite end is also formed into an eyelet 21 and is then turned at a right angle to the body of the link 19. The valve stem 90 17 is received by the eyelet 21, and is slidable therethrough. The stop 18 is engaged by the eyelet 21 when the link 19 is raised due to action of a push rod 30 which is operated to lift the flush valve 14. 95

In order that the flush valve 14 may be located and held in alignment above the outlet pipe 12 during its upward and downward movement, provision is made of a guide bar 22 having an enlargement 23 intermediate its ends. The enlargement 23 provides a stop for the float valve for the upward movement of the valve 14. 100

105 In the center of the enlargement 23, of the guide bar 22, is an opening 24, through which the valve stem 17 passes and is guided. The opposite ends 25 of the guide bar 22 are secured in substantially V-shaped slots 26 of projections 27 carried by the walls of the container 1, and are frictionally held therein. 110

A flared valve seat 29 is disposed immediately above the float valve 28, and is provided with an elongated sleeve extending through the cover plate 3 forming a vent for the container 1. Suitable fastening and packing means secure the valve seat 29 to the cover-plate 3.

A push rod 30 is connected with the float valve 28 and is provided with a hand piece 31 at its upper end. A shield 32, having a removable cover provided with an inwardly projecting hub portion 33, forms a guide means for the push-rod 30. Sufficient clearance is allowed between the push-rod 30 and the hub portion 33 to permit the passage of air into and out of the container 1. A flange 34 of the shield 32 permits fastening the shield to the cover plate.

As a further safeguard to the possible overflow of the container 1, due to the float valve 28 becoming water-logged, or off-seated, for any reason, provision is made of an overflow drain tube 35. The drain tube 35 has its upper end secured in the cover plate 3 and is in communication with the chamber formed by the walls of the shield 32. The drain extends downwardly and passes through an opening in the bottom of the container 1 to connect with the outlet pipe 12 below the flush valve seat. A suitable washer and lock-nut 36 provide a water-tight connection for the drain tube 35 and the container 1. Thus it will be readily understood that any water escaping past the float valve 28, and its seat 29, will be drained directly into the outlet pipe 12.

In operation, downward pressure is exerted by the hand upon the member 31, unseating the float valve 28, rocking the lever arm 19 and through the link and stem connections lifting the flush valve 14 from the seat 13. Water now flows out of the container 1 by way of the outlet pipe 12, to perform the flushing operation.

The opening of the vent which is controlled by the float valve 28 permits the escape of air which is confined above the water, relieving pressure, and allows water to flow into the inlet pipe 5. The water however flows out faster through the discharge pipe 13 so as to permit an efficient flushing operation.

When the valve 14 has descended far enough to shut off the discharge pipe water will continue to flow into the container until it reaches the float valve 28. It will carry up the float valve to its seat and thus shut off

the vent in the top of the container. The water will continue to flow into the container and will compress the air in the upper part 60 of the container until the pressure of the incoming water is equalized by the air pressure in the top of the container.

Various changes and alterations might be made in the general form of the parts described without departing from my invention and hence I do not limit myself to the precise details set forth but consider myself at liberty to make such changes and alterations as fairly fall within the spirit and scope of the appended claims.

I claim:—

1. A flush tank comprising a container having an outlet opening in its bottom, a valve for normally closing the outlet opening, a guide bar disposed above said valve, holding members carried by the walls of the container and provided with V-shaped slots arranged to frictionally hold the ends of the guide bar, said guide bar having a central opening, a valve stem for said valve arranged to pass through said opening, and means for lifting said valve stem.

2. A flush tank comprising a container having an outlet opening, a valve for normally closing the outlet opening, a guide member disposed above said valve, means carried by the walls of the container for releasably holding said guide member, said guide member having an opening, a valve stem for said valve arranged to pass through said opening, and means for lifting said valve stem.

3. A flush tank comprising a container having an outlet, a valve for normally closing the said outlet, guide means disposed within said container above said valve and in position to act as a stop member for the valve, means carried by the walls of the container for releasably holding said guide member, a valve stem for said valve arranged to be guided in its movement by said guide members, and means for lifting said valve stem.

4. In a flush tank, a container, a lever pivotally and removably mounted within the container, a discharge outlet, a valve for normally closing said discharge outlet and having connections to said lever, a ring seat at the end of said lever, a float removably carried by said ring seat and a push rod carried by the float, and extending through the top 110 of the container for operating the lever to cause the raising of the outlet valve.

THOMAS H. CHADWICK.
